US0D1085048S

(12) **United States Design Patent** (10) **Patent No.:** **US D1,085,048 S**
(45) **Date of Patent:** **** Jul. 22, 2025**

(54) **KEYPAD FOR LOUDSPEAKER**

(71) Applicant: **Osiviso Limited**, Huntingdon (GB)

(72) Inventor: **Douglas Samuel Roxburgh**, Suffolk (GB)

(73) Assignee: **Osiviso Limited**, Huntingdon (GB)

(**) Term: **15 Years**

(21) Appl. No.: **35/520,503**

(22) Filed: **Apr. 5, 2023**

(80) **Hague Agreement Data**

Int. Filing Date: **Apr. 5, 2023**

Int. Reg. No.: **DM/228527**

Int. Reg. Date: **Apr. 5, 2023**

Int. Reg. Pub. Date: **Apr. 5, 2024**

(30) **Foreign Application Priority Data**

Oct. 6, 2022 (GB) 6235743

(51) **LOC (15) Cl.** **14-01**

(52) **U.S. Cl.**

USPC **D14/217; D14/218**

(58) **Field of Classification Search**

USPC ..... D14/218, 217, 247, 341, 496, 138 AB; D21/517; 273/148 B; D13/168; D18/7; D10/65, 78; 340/4.37; 434/45, 27

CPC G05B 19/02; G06F 3/14; A63F 13/00

See application file for complete search history.

FOREIGN PATENT DOCUMENTS

WO D228527-001 * 4/2023

Primary Examiner — Paula Allen Greene

(74) *Attorney, Agent, or Firm* — Brooks Kushman P.C.

(57) **CLAIM**

The ornamental design for a keypad for loudspeaker as shown and described.

DESCRIPTION

1. Keypad for loudspeaker

1.1 : Front Perspective view

1.2 : Front view

1.3 : Back view

1.4 : Left side view

1.5 : Right side view

1.6 : Top view

1.7 : Bottom view

The broken lines illustrate portions of the keypad for loudspeaker that form no part of the claimed design.

1 Claim, 7 Drawing Sheets
